[57] CLAIM

The ornamental design for a face shield for hairdressers, as shown and described.

DESCRIPTION

FIG. 1 is a top plan view of a face shield for hairdressers,
showing my new design;
FIG. 2 is a front elevational view thereof;
FIG. 3 is a rear elevational view thereof; and
FIG. 4 is a side elevational view thereof, both side views being identical.
